UNITED STATES PATENT OFFICE.

JOHN B. WEEVER, OF EVANSVILLE, INDIANA, ASSIGNOR TO PAUL S. WEEVER, OF MEMPHIS, TENNESSEE.

COMBINED COLLAR-BUTTON AND TIE-HOLDER.

SPECIFICATION forming part of Letters Patent No. 761,118, dated May 31, 1904.

Application filed October 6, 1903. Serial No. 176,001. (No model.)

To all whom it may concern:

Be it known that I, JOHN B. WEEVER, a citizen of the United States, residing at Evansville, in the county of Vanderburg and State 5 of Indiana, have invented new and useful Improvements in a Combined Collar-Button and Tie-Holder, of which the following is a specification.

This invention relates to a combined collar-
10 button and tie-holder, and has for its object to provide a simple, inexpensive, light, and durable device of the character referred to which may be readily applied and removed and which when in place will afford a convenient and
15 efficient means for fastening the collar to the neckband of a shirt and will support the collar and cause it to lie flat against the neckband and prevent it from flaring outward and will hold the necktie in place on the collar.
20 To these ends my invention consists in the features and in the construction, combination, and arrangement of parts hereinafter described, and particularly pointed out in the claims following the description, reference
25 being had to the accompanying drawings, wherein—

Figure 1 is an enlarged perspective view of my improved device. Fig. 2 is a view showing it applied to a standing collar. Fig. 3 is
30 a similar view showing it applied to a turned-down collar, and Fig. 4 is a sectional view showing the device applied to a turned-down collar and having a bow-tie applied thereto.

In constructing my improved device a piece
35 of wire is bent back upon itself midway between its ends to form two bights 11, which together form a flat loop 2. The end portions of the wire are then bent rearwardly parallel to one another centrally of said loop to form a
40 shank 3. The two portions of the wire are then bent in opposite directions and are curved downwardly, as indicated at 4, in bow shape and are then bent vertically upward, as at 5, to a point considerably above the horizontal
45 plane of the loop 2, and the ends are finally bent vertically downward, as at 6, thus forming two loops 7, which are open at their lower ends. To the wire immediately in rear of the

shank 3 is rigidly attached a flat shank 8, to the rear end of which is attached a hinged 50 button 9 of ordinary and well-known construction. The flat shank 8 in practice may conveniently be attached to the wire by soldering it thereto, the solder 10 also serving to unite the two portions of the wire forming the shank 55 3 of the flat loop 2, or the shank may be secured to the wire by brazing or by any means suitable for the purpose.

In using my improved device the hinged button 9 is first turned down until it lies in 60 approximately the same plane with the shank 8, and it is then passed through the button hole or holes in the neckband of the shirt, after which the hinged button is turned at a right angle to the flat shank, as usual. The device 65 is thus attached to the neckband of the shirt and if the shirt is open in front also serves to secure the two ends of the neckband together. In applying the device to the neckband the flat shank 8 is so inserted in the button hole or 70 holes of the neckband that the free ends of the wire constituting the open loop 7 will project downwardly, as shown in Fig. 1 of the drawings.

If a standing collar is worn, the ends of the 75 collar are passed behind the loop 7, and the flat shank 2 of the wire-holder is passed through the buttonholes of the ends of the collar, as shown in Fig. 2 of the drawings. The loop 7 will thus project over the lower edges of the 80 collar ends and will hold the collar flat against the neckband of the shirt, thus preventing the collar from flaring outward, and will also hold the collar down in place neatly about the neckband. The ends of the necktie are passed 85 through the loops 7 outside the collar and are then tied, the tied portion of the necktie concealing the loops from view, the other portion of the device being concealed by the band. The necktie is thus prevented from riding up 90 on the collar, and the tie is held in its correct position.

The device may be used in the same manner with a turned-down collar excepting that the device is inverted, as shown in Fig. 3, and 95 the upturned end 6 of the loops in such case

lie between the two-folded portions of the collar. The ends of the tie in such case will pass between the ends 6 of the loops and the neckband portion of the collar and after the necktie has been tied will be held snugly in place.

If a bow-tie is to be worn (always, of course, with a turned-down collar)—that is to say, a tie known to the trade as a “butterfly-tie,” which comprises a piece of material tied in the form of a bow and sewed together to hold the parts in place and a stiff back, usually made of pasteboard or similar material and approximately crescent-shaped, the bow being stitched to such backing and provided on its rear side with an elastic loop 12—said elastic loop is buttoned over the flat loop 2, (the holder being in the position shown in Figs. 3 and 4,) and the ends of the backing 11 are passed through the open loops 7, and the latter hold the backing in place and prevent the same from tilting up or down at either end, thus holding the tie perfectly horizontal. Should the backing of such tie be not provided with the elastic loop or should such elastic loop become broken, stretched, or detached, as is very frequently the case, the bow will still be securely held in place, the loops operating to hold the ends of the bow up and within the collar, and the tie portion of the bow, which lies outside of the collar, operating to prevent any endwise movement of the bow, such result being obtained by the coaction of the bow and the collar edges.

By hinging the button 9 to its shank, as shown, the button may very easily and readily slip in and out of the buttonhole of the neckband of the shirt, and by providing the flat shank 8 the device is held in a horizontal position and prevented from turning in the buttonhole.

In removing the collar and tie it is unnecessary to remove the device from the neckband

of the shirt, and it may be left therein as long as worn.

Having described my invention, what I claim is—

1. A device of the character described, comprising a bow-shaped wire provided centrally with a flat loop extending in front of the bow and the wire bent at its ends to form vertical loops open at their lower ends, and a button rigidly attached to the rear central portion of the bow, substantially as described. 45 50

2. A device of the character described, comprising a bow-shaped wire provided centrally with a flat loop extending in front of the bow and the wire bent at its ends to form vertical loops open at their lower ends, and a hinged button rigidly attached to the rear central portion of the bow, substantially as described. 55 60

3. A device of the character described, comprising a bow-shaped wire bent at its ends to form vertical loops open at their lower ends and provided centrally with a flat elongated loop extending in front of the bow, a flat shank rigidly attached to the central rear portion of said bow, and a button hinged to the rear end of said shank, substantially as described. 65 70

4. A device of the character described, comprising a bow-shaped wire bent at its ends to form loops open at their lower ends and bent centrally to form an elongated flat loop which extends in front of the bow parallel therewith, a shank rigidly attached to the rear portion 75 of the bow in alinement with the shank of the flat loop, and a button hinged to the rear end of the flat shank, substantially as described. 70 75

In testimony whereof I have hereunto set my hand in presence of two subscribing witnesses.

JOHN B. WEEVER.
